UNITED STATES PATENT OFFICE.

TOMMIE C. NIX AND MACON D. MILLER, OF HAZEL, KENTUCKY, ASSIGNEES TO O. A. HARKER, JR., OF PURYEAR, TENNESSEE.

SELF-SERVICE STORE.

Application filed May 20, 1926. Serial No. 110,486.

This invention relates to a self-service store and it is an object of the invention to provide an arrangement wherein is provided an aisle having disposed along one side 5 thereof merchandise to be purchased and a continuous carrier traveling along the opposite side of the aisle, said carrier providing means whereby the articles selected by a customer may be carried to a checking station 10 to be claimed by the customer prior to exit.

It is also an object of the invention to provide a store system with an endless carrier comprising a plurality of hingedly connected baskets or containers adapted to receive various articles of merchandise as selected by the customer to relieve the customer the inconvenience of carrying such articles to a checking station or cashier.

The novel features of our invention will 20 hereinafter be definitely claimed.

In order that our invention may be the better understood, we will now proceed to describe the same with reference to the accompanying drawings, wherein:—

25 Figure 1 is a diagrammatic view in top plan illustrating a self-service store constructed in accordance with an embodiment of our invention;

Figure 2 is a fragmentary view partly in 30 vertical section and partly in elevation of a portion of the fixtures employed in connection with the system as herein disclosed;

Figure 3 is an enlarged fragmentary view 35 in top plan of the carrier as herein embodied;

Figure 4 is a fragmentary view partly in section and partly in elevation, the line of section being transversely of the structure shown in Figure 3.

40 As herein disclosed, our improved store system comprises a salesroom S provided with an entrance opening 1 preferably arranged at the transverse center of the room S and to each side of which opening may be arranged the front display windows 2.

Arranged at the central portion of the room S is an endless carrier C disposed somewhat in the fashion of an oval and arranged along and spaced from the side stretches of 50 the carrier C and substantially conforming to the inner end portion of such carrier are the shelvings 3 adapted to contain in desired arrangement the merchandise to be sold. By the shelving 3 it is to be understood that 55 we have in mind any store fixture which may

be employed for the display of merchandise and for which reason the portion 3' of the shelving is so constructed as to have arranged thereon vegetables, fruits or other perishable products. The rear portion of the 60 shelving is so constructed to provide a convenient entrance 4 to a rear storeroom R.

Within the field of the room S defined by the carrier C are suitably designed and constructed display counters 5 preferably arranged adjacent to the opposite ends of the carrier. Arranged between the forward counter 5 and the front end portion of the carrier C is a table 6 for the cashier or kindred attendant. The space between the 70 shelvings or store fixtures 3 and the carrier C constitutes an aisle A for the customers, the entrance to the aisle A being under control of the stile 7 and the exit under control of the stile 8.

75 The carrier C travels upon a continuous counter 9 supported as desired and such carrier consists of a plurality of baskets or containers 10 with adjacent baskets or containers in hinged connection.

80 To the under surface of the bottom of each of the baskets or containers 10 is secured a substantially V-shaped member 11 the apex of which being inwardly disposed with its extremities terminating adjacent to 85 the ends of such basket or container at one side thereof and extending slightly beyond said side of the bottom 12 of the container or basket 10. The extremities of each of the members 11 are pivotally connected, as at 90 14, with the extremities of the members 11 of the adjacent baskets or containers so that in the travel of the carrier the baskets or containers 10 are capable of requisite movement at the curved end portions of the path 95 of the carrier.

The bottom 12 of each of the baskets or containers 10 extends beyond the side of the basket or container proper and is provided therealong with an upstanding rack 15 disposed lengthwise thereof so that in the straight portions of the carrier the racks of adjacent baskets or containers 10 are aligned.

100 A suitably supported motor M is arranged within the field defined by the carrier C and drives a suitably supported shaft 16 carrying a gear 17 meshing with the racks 15 whereby the carrier C is caused to travel at desired speed.

110 Each of the baskets or containers 10, or

more particularly the bottom 12 thereof, is provided with the depending wheels 18 and 19, the wheel 18 traveling on a metallic track 20 disposed along the outer marginal portion of the counter 9 while the wheel 19 travels within a guide groove 21 disposed along the inner marginal portion of the counter 9. This guide groove 21 serves to cause the carrier C to have movement in a fixed path of travel. It is also to be understood that the hinged connections 14 hereinbefore referred to are at the inner side of the counter 9.

The outer portion of the counter 9 is provided therealong with an upstanding guard member 22 bridging the space between the counter 9 and the bottom 12 of each of the baskets or containers 10, the upper portion of the guard overlying an outwardly extended portion 12' of each of the bottoms 12. This guard provides effective means to prevent any articles or material falling or accumulating below the baskets or containers 10 which would otherwise hinder or obstruct the requisite travel thereof.

The forward end of the counter 9 has arranged therebelow a plurality of bins 23 while within the aisle A inwardly of but preferably in close proximity to the exit stile 8 is a customer counter 24 having an inwardly disposed extension 25 extending over or bridging the adjacent portion of the carrier C. When a customer first enters the store he is given checks or tickets all bearing the same number. He then passes through the stile 7 into the aisle A, selects an article from the shelves 3 after which he places such article together with a ticket in one of the baskets or containers 10. As the containers reach the station or bridge 25 the attendant at such station takes out the various articles and tickets and places them in the bins 23, the articles with similar tickets being placed in a selected bin. Before the customer makes his exit he notifies the cashier of his number and who in turn so informs the attendant at the bridge or station 25 who wraps up the articles assorted under such number in one of the bins 23 and 50 delivers the same to the customer over the counter 24.

Through the medium of the carrier C the customer is relieved of the necessity of carrying the various articles selected and the carrier C preferably carries at a speed in excess of that expected by the customer so that by the time the customer reaches the bridge or station 25 the cashier will have had full opportunity to itemize and list the various articles received under a common number and to total, preferably by an adding machine on the counter 6, the amount of the purchases so that as the customer makes his exit he can make the necessary payment with a minimum of hinderance and delay.

If desired, there may be arranged below the counter 9 and facing the aisle A suitable display shelving.

From the foregoing description it is thought to be obvious that a self-service store constructed in accordance with our invention is particularly well adapted for use by reason of the convenience and facility with which it may be assembled, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as herein-after claimed.

We claim:

In a store fixture, a supporting counter, spaced endless trackways upon the top of said counter, a plurality of containers having traction means movable over said trackways, V-shaped members attached to the bottoms of said containers with their ends projecting beyond one end of the containers, means for pivotally connecting the ends of the V-shaped members of adjacent containers, upstanding racks carried by the containers at one end thereof, and means engageable with the racks for imparting movement to the containers over the top of said supporting counter.

In testimony whereof we hereunto affix our signatures.

TOMMIE C. NIX.
MACON D. MILLER.
